Attorney.

UNITED STATES PATENT OFFICE.

RALPH K. MAKER, OF PROVIDENCE, RHODE ISLAND, ASSIGNOR TO JOSEPH GOLDSMITH,
JR., OF CHICAGO, ILLINOIS, DOING BUSINESS AS GOLDSMITH & HARZBERG.

COLLAR-CLASP.

1,322,805.

Specification of Letters Patent. Patented Nov. 25, 1919.

Application filed June 26, 1919. Serial No. 307,012.

To all whom it may concern:

Be it known that I, RALPH K. MAKER, a citizen of the United States, residing at Providence, in the county of Providence and 5 State of Rhode Island, have invented certain new and useful Improvements in Collar-Clasps, of which the following is a specification.

My invention relates to garment holders or 10 clasps and is particularly adapted to engage the opposite margins of soft turn down collars.

The essential objects of my invention are to insure such a firm grip of the device upon 15 the collar portions as to prevent accidental slipping, and without injury to the fabric; to enable the device to be used upon collars of different thickness; to enable quick assemblage of parts; and to attain these ends in an 20 inexpensive structure of maximum strength and facile to operate.

To the above ends essentially my invention consists in such parts and in such combinations of parts as fall within the scope of the 25 appended claims.

In the accompanying drawings which form a part of this specification,

Figures 1 and 2, are front and plan elevations respectively of my novel holder in 30 closed position,

Fig. 3, a plan of the same in open position, Fig. 4, a rear elevation of the same in closed position,

Fig. 5, a section on line 5—5 of Fig. 2.

35 Figs. 6 and 7, a plan and a rear elevation respectively of one end of my device with the lever and bearing member removed,

Fig. 8, a detail view of an operating member, and

40 Fig. 9, a front elevation of my holder applied to a collar.

Like reference characters indicate like parts throughout the views.

My holder comprises a bar 12 formed from 45 a strip of flexible or resilient metal whose ends are folded rearwardly and inwardly toward each other forming open loops 13 and resilient or vibratory arms 14, preferably slightly inclined forwardly to points adjacent the bar, where the material at the ends of the arms is bent upon itself to form substantially circular or closed loops 16. The

loops 16 and the adjacent portions of the arms are provided with longitudinal slots 19.

Each closed loop embraces a bearing or 55 pivot member consisting, in the present case, of a tubular body 21 with upset ends forming flanges 22 compressed from cylindrical form by a punch against the opposite edges of the loop 16.

60 Operating members are pivotally mounted upon the bearings. Each consists of a cam plate 24 having a peripheral cam shoulder 25 and provided with a central opening 26 to loosely fit upon its bearing member. Integral with the cam 24 is a lever arm 28 provided with a tapering enlargement 29 upon its end having a lateral shoulder or projection 30. The shoulder 25 and lever arm are 65 angularly disposed with relation to each 70 other on the periphery of the cam.

The operation of my device is as follows: The device is initially in open position as shown in Fig. 3. That is to say the levers 28 are amply spaced from their adjacent 75 loops 14, and the cam shoulders 25 are out of contact with the bar 12. The lever arms are next manually pressed downwardly toward the loops 14 with the corners 32 of the collar therebetween and the enlarged lever 80 portions 29 are snapped and maintained gripped tightly against the loops by virtue of the cam shoulders 25 which meanwhile have traveled into contact with the bar. This cam movement is freely permitted by reason 85

of the resiliency or vibratory character of the arms 14. The resilient arms 14 coöperate with the cam shoulders to maintain the parts in closed position as shown in Fig. 2 where it will be noted that the bearing members are 90 more remote from the bar 12 than is the case in Fig. 3. It will be observed further all the parts except the bearings 21 are stamped and cut from thin sheet metal, and that these bearings, which are ordinary eyelets, are 95 easily assembled and incorporated in the structure.

I claim:—

1. A collar or garment clasp comprising a bar, resilient oppositely directed vibratory 100 arms upon the same side of the bar, cams pivotally supported in the adjacent ends of the arms adapted to engage the bar, and lever arms on the cams.

2. A collar or garment clasp comprising a bar, resilient oppositely directed arms upon the same side of the bar, locking cams carried by the arms coöperating with the bar, lever arms on the cams, and projections on the lever arms adapted to contact with resilient arms.
3. A collar or garment clasp comprising a bar, resilient oppositely directed arms upon the same side of the bar, lever arms pivotally supported by the resilient arms, and means

upon the lever arms engaging the bar for locking the lever arms against movement from the resilient arms.

4. A collar or garment clasp comprising a bar, oppositely directed arms upon the same side of the bar, cams pivotally supported on the adjacent ends of the arms adapted to engage the bar, and lever arms on the cams.

In testimony whereof I have affixed my signature.

RALPH K. MAKER.
